(57) **CLAIM**

The ornamental design for a double handled clipboard, as shown and described.

DESCRIPTION

FIG. 1 is a top plan view of a double handled clipboard, in accordance with the present invention.

FIG. 2 is a front plan view of the double handled clipboard shown in FIG. 1.

FIG. 3 is a right side elevational view of the double handled clipboard shown in FIG. 2; and,

FIG. 4 is a front isometric view of the double handled clipboard shown in FIG. 2.

The broken lines showing the clip in FIGS. 1–4 of the drawings are for information purposes only and form no part of the claimed design.
